ROAD MARKER

Filed April 25, 1927

UNITED STATES PATENT OFFICE

GILMORE N. HERMAN AND ALBERT W. T. MOHR, OF CHICAGO, ILLINOIS, ASSIGNEES
TO ALLOY STEEL CORPORATION, OF CHICAGO, ILLINOIS, A CORPORATION OF
ILLINOIS

ROAD MARKER

Application filed April 25, 1927. Serial No. 186,200.

Our invention has to do with the marking of streets and other roadways, for the prevention of accidents by regulating traffic at intersecting points, as direction signals, and for other purposes. The large volume of 5 automotive vehicle traffic over streets and roadways has made necessary the provision of means for guiding traffic at street corners and road intersections, and an expedient quite generally adopted for that purpose is to paint 10 a narrow white stripe across the right hand half of the street or road at the near side of an intersecting street or road crossing. This practice is, however, objectionable because the paint very quickly wears off, making it 15 necessary to repaint the stripe at frequent intervals, at large expense for labor and material. Beside, on roadways where there is more or less dust the stripe is apt to be covered and hidden by the dust so that it cannot 20 be observed by an approaching driver in time for him to stop or slow down his vehicle before reaching the crossing. Recognizing these disadvantages of the use of a painted 25 stripe it has been proposed to substitute for it metal markers adapted to be embedded in the roadway. These markers are of various designs and have been made of materials of different kinds, but so far as we are aware 30 none of them has proven entirely satisfactory, for various reasons, among which may be mentioned the high cost of manufacture; lack of proper wearing qualities, with consequent large expense of maintenance, and a tendency 35 to rust, thereby reducing, if not entirely destroying, the visibility of the marker except on near approach to it. The object of our invention is to avoid these and other objections to existing road markers, which object 40 we accomplish as illustrated in the drawings and hereinafter described. What we regard as new is set forth in the claim.

In the accompanying drawings,—

Figs. 1 and 2 are perspective views, from 45 different angles, of one of the sections of which our improved marker is generally composed;

Fig. 3 is a fragmentary vertical cross-section of our improved marker as installed in a 50 street or roadway;

Fig. 4 is a diagrammatic view illustrating a street intersection showing the manner in which the marker is preferably used;

Fig. 5 is a plan view of our improved marker as designed for use as a direction sign; and 55

Fig. 6 is a plan view of our improved marker designed for use as a sign to indicate a route, or for other purposes.

It is of the utmost importance that a road marker such as has been referred to be made 60 of a material that possesses great lasting qualities, not only as to its resistance to abrasion, but also as to its liability to fracture under the stresses to which it is subjected by traffic flowing over it, temperature 65 changes, &c.; also that the material be of such character that it will resist corrosion and abrasion and will maintain a bright polished surface without attention, so that it will be readily visible from a considerable distance, 70 so as to give the drivers of approaching vehicles ample warning that they are approaching a street or road intersection. It is also important that the material be of such character that the marker may be manufactured 75 without difficulty and at a cost that will not be prohibitive.

We have discovered that a material that satisfies the requirements is an alloy steel containing from six to twenty-five per cent chromium, from one-half per cent to twenty per cent nickel, and not over one per cent carbon. Such material is capable of taking a high polish, and does not abrade, corrode or 80 rust under the action of the elements, or other influences to which it is likely to be subjected when used as a road marker; consequently it always remains bright, and because of its reflection of light is visible from a great distance. Also, dust does not adhere to it, and, 85 therefore, it is not likely to be hidden by the accumulation of dust upon it, since it would be swept clean by any breeze strong enough to raise dust.

In applying this material to the construction of a marker it is cast or rolled in sections or strips which, in the best embodiment of our invention, have the shape shown in Figs. 1 and 2. These strips, which in their completed form are of comparatively short length, 100

say about thirty inches long, are T-shaped in cross-section and comprise a substantially flat top surface 7 which is polished, and, when the marker is in place, lies flush with the top surface of the roadway, as shown in Fig. 3, in which 8 indicates the road surface, of asphalt, concrete or other suitable material, and 9 the foundation. Projecting from the under surface of the strip, and preferably midway between its side margins, is an anchoring flange 10 which is integral with the top surface of the strip and is adapted to be embedded in the foundation of the roadway, where it is firmly anchored in place. The flange 10 may if desired be of uniform length, but preferably it is cut away to provide a number of anchoring members or feet 11 spaced at intervals along the length of the strip, as shown in Figs. 1 and 2. These anchoring members are preferably slightly tapered toward their outer margins, as shown in the drawings, and are provided with transverse perforations 12 for the reception of anchor bars 13 which extend through them, as shown in Fig. 3. These anchor bars are also embedded in the foundation of the roadway, and serve to firmly anchor the marker in place. The bars 13 are designed to fit loosely enough in the perforations 12 so that they can readily be inserted at the time the marker is being installed. In installing the marker a sufficient number of sections or strips are employed to give the desired length, usually half the width of the roadway, the sections being laid end to end and each separately anchored in place, thereby minimizing the danger of its becoming loosened, and facilitating road repair work, since in many cases it will suffice to remove a single section rather than the entire marker, as where only a small part of the road must be torn up for repair, or for underground construction work. In Fig. 4 we have shown each marker as a whole made up of five sections, but their number may, of course, be varied as circumstances dictate.

In Fig. 5 we have shown our invention as embodied in a curved arrow 14 used as a direction sign, and in Fig. 6 we have shown it as embodied in a letter 15 used as a route indicator, or for other purposes. In either case the strip or section will be embedded in the roadway and anchored in the same way as that above described.

By making our improved marker of the material and in the form described, not only the exposed upper surface, but also the parts embedded in the ground, do not corrode, and, therefore, the marker does not deteriorate even with long continued use. In fact, it will outlast the roadway in which it is placed, and as its exposed surface retains its polish it requires no attention to keep it in effective condition. Our invention, however, in its broadest aspect includes the provision of integral anchoring means for the exposed top surface

of the marker, such as the flange 10, of such character as to give the marker the necessary rigidity, whether the anchoring portion be made of the same material as the top surface or not. In some instances it may be desired to use a different material for the anchoring means and to unite it with the top surface by welding to form an integral structure, but the marker may be more easily manufactured and possesses greater lasting qualities if made of the same material throughout, and, therefore, that construction is preferable. By making the marker as a whole in sections as described, expansion and contraction may be compensated for, so that there is no danger that the setting of the marker with reference to the road surface will be disturbed under extremes of heat and cold.

What we claim as our invention and desire to secure by Letters Patent, is—

A marker of the character described comprising an integral metal strip having a polished top surface, and a plurality of tapered anchoring members projecting at spaced intervals from the under surface thereof, said members being perforated for the reception of transverse anchor bars.
